UNITED STATES PATENT OFFICE

JESSE HERLIN TROMANHAUSER, OF MINNEAPOLIS, MINNESOTA.

CONCRETE SEA-WALL.

No. 891,966.

Specification of Letters Patent. Patented June 30, 1908.

Application filed October 5, 1907. Serial No. 396,084.

To all whom it may concern:

Be it known that I, JESSE HERLIN TROMANHAUSER, of the city of Minneapolis, in the State of Minnesota, one of the United States of America, architect, have invented certain new and useful Improvements in Concrete Sea-Walls, of which the following is the specification.

My invention relates to improvements in concrete sea walls, and the object of the invention is to devise a simple construction of concrete wall which may be built in sections of any desired size and in a sheltered harbor and then floated to its position and sunk and it consists essentially of a pontoon formed of outer longitudinal and connecting cross timbers suitably braced together and provided with a suitable flooring, outer longitudinal walls of concrete built up on the longitudinal 20 timbers which form the base for the wall and cross connecting concrete walls built up from cross timbers which form a base for the walls, a water cock for admitting water into the hollow interior, a suitable filling for the interior and a top formed of concrete as herein-after more particularly explained by the following specification.

Figure 1 is a general perspective view of my sea wall partially broken away and in section and in course of construction. Fig. 2, is a cross section through Fig. 1. Fig. 3 is a longitudinal sectional view through Fig. 1. Fig. 4 is a similar view to Fig. 2, of a complete wall.

In the drawings like letters of reference indicate corresponding parts in each figure.

A is the pontoon which is formed by the longitudinal timbers A' and A² the cross connecting timbers A³, the supplemental cross timbers A⁴, the flooring A⁵ secured beneath the cross timbers A³, the verticals A⁶ connected together by the longitudinal timber A⁷ and the truss bars A⁸ which are secured to each end of the cross timbers A³ by bolts A⁹ (see Figs. 2 and 4) which have upwardly extending hooked ends for a purpose which will hereinafter appear.

A¹⁰ is a curb wall extending all around the pontoon and formed by the sheeting A¹¹ secured to the longitudinal timbers A' and A² and the longitudinal planks A¹² secured by the hooked bolts A¹³.

B and B' are the longitudinal and cross walls formed of concrete suitably reinforced by the steel truss bars.

D is a filling of stone or any other suitable

material such as gravel, sand or clay, (see Fig. 4).

E is a water cock secured in one of the outer concrete walls and E' are openings formed at the base of the cross walls B' for the purpose of allowing the water admitted to one compartment to flow into the adjoining compartments.

A¹⁴ is the top formed of concrete.

Having described the principal parts involved in my invention I will briefly describe the method of constructing the same.

The pontoon A is first completely constructed on land and then floated in sheltered water. The walls B and B' are then built up on the longitudinal and cross timbers A', A² and A³ respectively by any suitable method used for the building of concrete walls and in courses, the mold F being moved up as the wall is built. As each layer of the walls are formed, the pontoon gradually sinks a proportionate distance and is ballasted to prevent the same from capsizing. The hooked ends of the bolts A⁹ and A¹³ are embedded in the concrete wall as shown thereby securely anchoring the walls to the pontoon. When the walls B and B' are nearly completed the pontoon is towed to the place at which it is to be sunk. The water cock is then opened to flood the interior of the wall and the structure is thereby sunk into place. If the walls should not settle evenly and satisfactorily the water may be pumped out from the interior of the wall to refloat the structure which then may be again sunk. The interior of the wall is then filled with rock, sand gravel, or any other suitable filling. It will be understood that the top of the wall when sunk will be above the surface of the water and after it is sunk the final layer of concrete and the concrete top is built.

From the description it will be seen that I have invented a sea wall which is simple in structure and which may be built in any sheltered water desirable and when near completion may be floated to the desired place and sunk.

What I claim as my invention is:

1. A concrete sea wall comprising a base of box form and suitably trussed, concrete walls built upon the aforesaid base and a suitable filling for the interior as and for the purpose specified.

2. A concrete sea wall comprising a base formed of longitudinal and cross timbers

suitably trussed, a suitable bottom secured beneath the timbers, concrete walls built upon the longitudinal and cross timbers, and a suitable filling for the interior, as and for the purpose specified.

3. In combination a buoyant base formed of longitudinal and cross timbers suitably trussed, a suitable bottom secured beneath the cross timbers, concrete walls built upon the longitudinal and cross timbers and means for sinking said base as and for the purpose specified.

4. A concrete sea wall comprising a pontoon base formed of longitudinal and cross timbers suitably trussed, a suitable bottom secured to and beneath the cross timbers, side and end walls built upon the longitudinal and end cross timbers and cross connecting walls built up on intermediate cross timbers and a suitable filling and top to the wall as and for the purpose specified.

5. In combination a buoyant base formed of longitudinal and cross timbers suitably trussed, a suitable bottom secured to and beneath the cross timbers, side and end walls built up on the longitudinal and end cross timbers, cross connecting walls having open-

ings extending through the wall in proximity to the base and means for admitting water through one of the outer walls as and for the purpose specified.

6. In a concrete sea wall, a base comprising the side longitudinal timbers, the cross connecting timbers, a flooring secured to and beneath the cross timbers uprights secured centrally of the cross timbers, a longitudinal timber bridging the uprights, and cross trusses secured to the outer ends of the cross timbers and extending over the longitudinal bridge timbers as and for the purpose specified.

7. The method of constructing a sea wall comprising the building of a pontoon on land, the floating of the same in a sheltered place, building concrete walls in the outer edge of the pontoon, flooding the structure to sink the same, filling the interior with a suitable filling and completing the upper portion of the wall after the structure is sunk, as and for the purpose specified.

JESSE HERLIN TROMANHAUSER.
